CLAIM

The ornamental design for a communication device for hard plastic masks, as shown and described.

DESCRIPTION

FIG. 1 is a top perspective view of a communication device for hard plastic masks;

FIG. 2 is a bottom perspective view thereof;

FIG. 3 is a front view thereof;

FIG. 4 is a rear view thereof;

FIG. 5 is a top view thereof;

FIG. 6 is a bottom view thereof; and,

FIG. 7 is a left side view thereof, the right side being a mirror image of the left side.

The broken lines in the drawings illustrate portions of the communication device for hard plastic masks that form no part of the claimed design.
